CLAIM

The ornamental design for an animal control device, as shown and described.

DESCRIPTION

FIG. 1 is a front view of an animal control device showing my new design.

FIG. 2 is a rear view thereof.

FIG. 3 is a right side view thereof.

FIG. 4 is a left side view thereof.

FIG. 5 is a top view thereof.

FIG. 6 is a bottom view thereof.

FIG. 7 is a right front perspective view thereof.

FIG. 8 is a left front perspective view thereof.

FIG. 9 is a right rear perspective view thereof.

FIG. 10 is a left rear perspective view thereof; and,

FIG. 11 is a left front in-use perspective view thereof.

(Continued)

The broken lines depict environmental subject matter and form no part of the claim.
